UNITED STATES PATENT OFFICE.

JESSE R. THOMAS, OF KANSAS CITY, KANSAS, ASSIGNOR TO LEWIS H. BORSERINE, OF KANSAS CITY, MISSOURI.

STOVE.

Application filed March 27, 1924. Serial No. 702,264.

To all whom it may concern:

Be it known that I, JESSE R. THOMAS, a citizen of the United States, residing at Kansas City, in the county of Wyandotte 5 and State of Kansas, have invented certain new and useful Improvements in Stoves; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to stoves. It is primarily intended as a heating stove although it is adapted to be used as a cook stove. The primary object of the invention is to provide a stove with an oil burner, the main 20 body of the stove being in the form of a drum with vertical flues. The stove is provided with a coal grate so that in the event the oil supply becomes exhausted, coal may be used, however I prefer to utilize the oil 25 burner for providing the necessary heat.

In the drawings,

Fig. 1 is a perspective view of a stove constructed in accordance with my invention, part of the drum wall being broken away 30 to illustrate the flues and part of the coal grate.

Fig. 2 is a horizontal sectional view through the stove.

Fig. 3 is a horizontal sectional view 35 through the oil burner, and

Fig. 4 is a perspective view of the oil burner, part of the vaporizing chamber being shown in section.

The drum 1 is of appropriate construction 40 and it is provided with a door 2 at the front so that access may be had to the coal grate 3 and to the interior of the drum. Within the drum is a plurality of upstanding flues in staggered relation. The flue 4 immediately in rear of the grate is elongated transversely of the drum. It is connected to the bottom 5 in any appropriate manner and it 45 opens to atmosphere at the bottom.

At the top of the flue 4 are two laterally 50 diverging tubular branches 6 and 7 which communicate with atmosphere through the side of the drum 1. In rear of the flue 4 in spaced relation therewith and in spaced relation one with the other are two vertical flues 8 and 9, each having a lateral exten-

sion. The lateral extension 10 for flue 8 communicates with atmosphere through one side of the drum 1 and the extension 11 for flue 9 communicates with atmosphere through the opposite side of the drum 1.

In rear of the flues 8 and 9 is a flue 12 corresponding with flue 4 and it is provided with lateral extensions 13 and 14 like the extensions 6 and 7 for the flue 4 so the flues 4 and 12 may be termed double flues while the flues 8 and 9 are single flues. The flues do not extend entirely to the top plate 15 of the stove but terminate short thereof so that the products of combustion may flow around and between the flues in a tortuous manner 70 because the flues provide a tortuous passageway. The products of combustion cannot pass directly out through the stove pipe opening 16 because there is a lateral baffle 17 over the flue 12, consequently while the products of combustion may pass around the flues 4, 8 and 9 and over them as well as they can pass around the flue 12, but not over it on account of the baffle 17, therefore 75 the products of combustion will efficiently 80 heat the flue and the air within them. Since hot air has a tendency to rise, it will be obvious that the cold incoming air, as soon as it becomes heated in the flue, will tend to rise and pass out through the extensions into 85 the room.

The burner for the stove is of novel construction. It is provided with a casing 18 having air inlet openings 19 and 20 to support combustion. Within the casing 18 is a horizontal or substantially horizontal vaporizing chamber 21 into which the oil may flow from a pipe 22 provided with a valve 22' so that the effective port area of the pipe 22 may be controlled. The vaporizing 90 chamber 21 is provided with outwardly inclined sides 23 and 24 and an offset bottom portion 25 with inclined sides 26 and 27, inclined in opposite directions to the complementary sides of the main portion 95 of the vaporizing chamber so as to provide triangular flame deflectors, spaced apart with the acute angles of the deflectors, substantially in line with the burner tips 28 and 29 controlled by the valves 30 and 31. The burner tips are supplied with fuel from a connection 32 communicating with the interior of the vaporizing chamber and with a manifold 33. The angles 34 and 35 of the 100 deflectors are preferably not exactly in line 105 with the acute angles of the deflectors, substantially in line with the burner tips 28 and 29 controlled by the valves 30 and 31. The burner tips are supplied with fuel from a connection 32 communicating with the interior of the vaporizing chamber and with a manifold 33. The angles 34 and 35 of the deflectors are preferably not exactly in line 110

2
with the tips but they are so disposed that about two-thirds of the flame from the tip 28 will be directed on the outside of the deflector having the point 34 and about two-thirds of the flame from tip 29 will be directed on the outside of the deflector having the point 35. One-third of the flame from each tip 28 and 29 will be directed inwardly so the deflectors divide the flame into three equal parts and since the deflectors are spaced apart, the flame will be spread over a relatively wide area, permitting the products of combustion to contact with the maximum part of the first flue 4, and thus distributing the products of combustion throughout the tortuous passageway formed by the staggered flues.

The combustion chamber may be constructed of heavy sheet metal or it may be cast if desired. A primer may be used to heat the manifold when the burner is first started, but after the burner is operating the flames from the tips or nozzles 28 and 29 will maintain the vaporizing chamber at sufficient temperature to vaporize the fuel and the air will be supplied through the ports 19 and 20. The lid 15 may be swung upon a hinge 36 of appropriate construction.

30 It will be apparent that the invention can be inexpensively constructed and that the flues and drum will afford a relatively large radiating surface so that the stove will admirably serve as a heating stove and while I prefer to operate the stove as an oil burning stove, using hydrocarbon fluid as the fuel, it is obvious that coal or wood may be burned on the grate 3 if desired.

What I claim and desire to secure by Letters Patent is:

1. A hydrocarbon burner comprising a hollow vaporizing chamber having a forwardly extending portion with flat parallel walls and two offset depending wall por-

tions having inclined sides spaced apart with 45 the narrowest space at the rear of the chamber, means for feeding fuel into the chamber and nozzles immediately adjacent to the flat portion for directing flame against the inclined sides of the chamber. 50

2. An oil burner comprising a hollow vaporizing chamber having forwardly inclined sides and offset portions, said offset portions having rearwardly inclined sides to provide spaced triangular flame spreaders, nozzles 55 communicating with the chamber and mounted to direct flame against the spreaders and means for feeding liquid hydrocarbon fuel into the vaporizing chamber.

3. A hydrocarbon burner comprising a 60 hollow vaporizing chamber, the hollow vaporizing chamber being horizontally disposed and having depending triangular offset portions with apexes of the angular portions directed toward the front of the 65 chamber, the forward portion of the chamber extending beyond the apexes and having spaced flat walls, nozzles for directing flame against the apexes of the angular portions, the angular portions being spaced 70 apart, the inner walls of the angular portions converging toward the rear of the chamber so that the narrowest space between the walls of the angular portions will be at the rear of the chamber and means for communicating the nozzles with the chamber. 75

4. A hydrocarbon burner comprising a horizontal hollow vaporizing chamber having converging side walls, the chamber having triangular offset portions depending below the major portion of the chamber and burner nozzles in line with the apexes of the offset portions for directing flame against said apexes and a pipe communicating the nozzles with the vaporizing chamber. 80 85

In testimony whereof I affix my signature.

JESSE R. THOMAS.
